UNITED STATES PATENT OFFICE.

WILLIAM W. ODELL, OF WASHINGTON, DISTRICT OF COLUMBIA.

GAS PRODUCER FOR USE WITH AUTOMOTIVE MECHANISMS.

Application filed December 7, 1921. Serial No. 520,580.

To all whom it may concern:

Be it known that I, WILLIAM W. ODELL, a citizen of the United States, residing at Washington, D. C., have invented certain new and useful Improvements in Gas Producers for Use with Automotive Mechanisms, of which the following is a specification.

The ordinary type of gas producer as used with various fuels is not suitable for use on motor vehicles even when made of a size proportional to the gas demand. The brick work in such a producer, when sufficiently light, will not stand the vibration; the fuel storage capacity is too small; the wearing parts are not quickly and easily replaceable; gas can not be generated rapidly enough after a brief shutdown or stop; fuel can not be charged without interfering with the gas supply; and the cooling system is not as economical as is necessary for this purpose. Also the control of moisture admitted to the generator is not automatic in present apparatus. It is my object to provide a gas producer with cooling system, suitable for use on motor vehicles, power boats, locomotives, cars, traction engines, and the like, and also for small power units, and which has the following particular and characteristic features:

- (1) An unusually large fuel storage magazine.
- (2) A means of charging fuel into magazine without interfering with the gas supply.
- (3) A means of removing ash and clinker without interfering with the gas supply.
- (4) A reverse valve connection whereby the producer can be instantly converted from a down draft producer to an up draft producer, or vice versa.
- (5) A means of cooling the gas by both air and water in one apparatus.
- (6) A means of cooling and purifying the gas and simultaneously recovering the heat transferred in the process of cooling.
- (7) A device for forcing air into the cooler and generator by means of the motion of the vehicle, thus reducing the vacuum on the engine.
- (8) A cushion suspended, quickly removable and replaceable generator lining consisting of but one or at most a few parts and bottomless or nearly so.
- (9) A generator lining suspended in the

air used for gas making for the purposes of cooling the outer casing and preheating the air.

(10) A quickly removable hopper base (magazine base) which forms an annular gas off-take space for up draft gas, and which is so designed as to support the weight of the fuel in the magazine.

(11) A generator without a grate or tuyères.

(12) A means of starting and producing combustible gas quickly after brief stand-by periods by the use of liquid or colloidal fuel enricher.

(13) A generator with a carbonizing chamber for carbonizing and driving off the tarry vapors from wood and other fuels.

(14) A combination in a producer of a suction and a pressure producer; the amount of air supplied under pressure being quite a definite relative amount.

(15) A means of automatically and uniformly distributing the water over the surface of the gas cooler and automatically regulating the supply of moisture to the generator.

(16) An air cooled producer shell with means for circulating the air for the purpose of reducing radiation losses.

(17) A means of preventing the filler in the purifier from bunching in the middle and permitting the gas to pass up around the walls.

In Figure 1 is shown a vertical sectional view of the producer and gas cooler complete.

Figs. 2, 3 and 4 are detail views partly in vertical section and partly in elevation showing various modified forms of the generator pot or producer lining which have been found satisfactory in my apparatus.

Figs. 5, 6 and 7 are plan sections on lines 5—5, 6—6 and 7—7 of Figs. 2, 3 and 4 respectively.

It will be noted that the various parts of the producer are lettered in capitals while the cooler and other parts are designated by small letters.

In Figure 1 A is the storage magazine for the fuel supply, B is the outer shell of the producer proper, C is the air space between inner and outer shells, D is the generator pot or producer lining, E and E₁ are the packing ring supports for the generator pot, F is the air intake to the air space

surrounding the producer, G and H are the off-takes for the gas made when the producer is operated as an up draft and down draft producer respectively. I is the valve 5 through which the gas all passes on its way to the cooler after leaving the producer. J is the lever used to operate the valves K and L which make the producer an up draft or a down draft producer accordingly as the 10 air is admitted through L or K respectively. Preferably the gas valve I is connected to the blast valve operating lever J whereby it may be operated in synchronism with the air valves L and K. M is the hopper base 15 (fuel magazine base) and N is the annular space for gas when the producer is operated by up draft and for air when operated as a down draft producer. O is the fuel bed in the generator pot, P is the air space in 20 which the generator pot is suspended, Q is the ash pit and R is the door for removing ashes. S is the blower for starting a fire in the generator pot or for bringing fuel bed up to operating temperature after 25 standby periods. T is the liquid fuel storage tank and U is the valve controlling the supply of liquid fuel to the fuel bed. V is an insulating covering of the producer, W is the lid of fuel magazine and X is the 30 floor supporting the ashes and fuel. The parts designated by small letters are as follows: a is the air inlet to the purifier and cooler which latter has an outer shell b and an inner shell c with baffles d in between. 35 e is the outlet for hot air from cooler; f is the water reservoir for supplying water to the cooling surface and g is the water supply pipe to this reservoir. h is the wicking or fibrous surface surrounding shell c, 40 and i is a wire gauze or screen surrounding and holding wicking h in place. k is the producer gas offtake from the cooler to the engine not shown, and r is the gas inlet to cooler. m is the liquid seal and n is the 45 automatic overflow for tarry matter or other condensate. z is a dust clean-out and drain for excess water fed to cooler; p is a screen over air inlet a. The rings for holding the purifying material in place are shown at r, 50 and s is the purifying material. To operate this producer I proceed as follows:

A fire is kindled in D Fig. 1 and fuel is added till the magazine A is about full. The cover W is left open and the air fan S is started, supplying air to the fuel bed 55 from beneath, and blasting is continued until the fuel bed is sufficiently hot for gas making purposes. During this blasting period valve I is turned so that none of the blast gas can pass out through it. The cover W is now closed and the blast from S discontinued and valve I is turned as shown in Fig. 1. Lever J is also placed in position as shown in Fig. 1, so that the producer air supply comes through F into air

space C around the producer and through valve L to the fuel bed from beneath, and gas is generated in fuel bed O by the well known producer gas reactions. The engine is started and sucks the gas from the producer by the following route: gas from fuel bed O passes to space N above fuel bed, through off-take G and valve I, thence through pipe x to the cooler and purifier, through filling material s and out through 75 h and q to the engine. The complete course of the air to the producer is from p around the inner shell of the cooler as directed by baffles d, out through e and F to C and from there to the fuel bed through valves K or 80 L according to the position of lever J.

At times I find it desirable to operate the producer as a down draft producer for the purposes of maintaining a more uniform temperature in the fuel bed; relieving 85 clinker troubles by changing not only the temperature in the lower fuel mass but also the nature of the atmosphere prevailing in this zone; preventing the passage of excess of fuel into the ash; for carbonizing fuel 90 and for cracking oil or other liquid fuel. By operating lever J so that either valves K or L are open, and thus simultaneously adjusting valve I to take the gas from H or from G accordingly, the producer is at 95 once a down draft or an up draft producer. This arrangement permits charging the fuel magazine without interfering with the gas supply since during this period the producer is operated as a down draft producer. 100 Likewise the ash is removed through the cleanout door R without affecting the gas supply since during this operation the producer is operated as an updraft producer.

As the gas from I passes through dip pipe 105 v and seal m and on through the cooler it is not only cooled but is also purified and freed from tarry matter by contact with purifying material s which may be glass wool, mineral wool, or other contact material. 110 The sensible heat of this gas is imparted to the metal shell c which is so arranged that water coming into the reservoir f from g overflows and uniformly distributes itself over the surface c by means of the wicking 115 or fibrous material arranged at h around c for this purpose. This wicking not only distributes the water uniformly over the surface c but, due to the greater surface exposed and the nature of the material, a more 120 rapid evaporation takes place and a greater cooling action results. In this manner it is possible to supply the producer with air of a higher degree of saturation than otherwise. When the valve I is directly connected to the lever J it is evident that the gas regulating means and the air valves will be 125 operated in synchronism, the moving parts controlling both the air supply and the direction of the gas. It should be noted that 130

the supply of moisture is automatically controlled, for obviously when the fuel bed is not particularly hot the gas will not impart as much heat to the shell *c* as when the fuel bed is very hot under which latter condition the temperature of the gas leaving producer is higher and consequently more evaporation takes place per unit volume of air space surrounding *c*. This increase in the moisture content of the air causes a greater cooling of the fuel bed and affords an automatic check on sudden temperature changes in the fuel bed.

The air which comes into the outer shell *b* of the cooler and through *p* under pressure—(due to the motion of the vehicle with *p* facing towards the direction of travel)—also aids in cooling the gas and condensing the tarry matter since its temperature is increased in passing to *e*. This moist air is further heated in air space *C* surrounding producer. The air is forced to travel around the producer since it is supplied at the opposite side from which it enters the producer proper through valves *K* and *L*.

I find that the generator pot *D* is best able to withstand vibration and shock when it is suspended on packing rings as shown at *E* and *E*₁ which are capable of absorbing the shock. These rings constitute a cushion suspension for the generator pot *D* and also afford a means of sealing chamber *N* from chamber *P*. This generator pot is suspended in the air from which the producer gas is made and the hottest part of the pot is most exposed thus allowing the maximum superheating of the moist air and the minimum amount of radiation.

While in the present embodiment of the invention packing rings are employed for the purpose of absorbing the shock and vibration of the generator pot incident to road travel, it is obvious that other cushioning means may be employed. For example, generator pot *D* might be suspended from the outer casing of shell *B* by means of springs or other shock absorbers.

A large part of the weight of the fuel is supported by other means than by the fuel or generator pot which feature prolongs the life of the latter. The weight of the fuel is supported largely by the bottom lining *X* and by the removable hopper bottom *M* which is designed to support the weight of the fuel in the magazine *A*.

I have found that after a stand-by period when the temperature in the fuel bed is not high enough to allow the immediate production of the best quality gas a quick start can be made and without inconvenience by admitting a small amount of liquid fuel through valve *U* into the fuel bed; this can be done regardless of whether the producer is being operated as a down draft or as an up draft producer. When the oil used is

relatively heavy and the temperature in the fuel bed is comparatively low, the producer should be operated as a down draft producer during the oil injection to promote gasification and cracking of the oil, but with light oils this is not necessary. While the oil is being admitted the producer is operated in the usual manner and the lean producer gas is enriched with oil gas and the engine can be started at once. When the producer gas is sufficiently rich to run the engine the oil supply is shut off by closing valve *U*. The same result may be accomplished without the use of oil by employing air blast *S* meanwhile wasting the lean gas by opening valve *t* provided for the purpose.

This producer is so designed that wood or other fuel can be carbonized and subsequently used as fuel in the same apparatus which I find enables me to use wood chips and other cheap fuel, particularly when the producer is not in continuous use twenty four hours a day. To accomplish this I fill the chamber *A* with wood chips or other fuel, preferably just after a shut down, and leave lid *W* partly open; after standing over a limited period of time the wood is converted into charcoal due to the action of heat with an insufficient supply of air for complete combustion. When the carbonizing time is brief and the action must be hurried I open the ash-pit door slightly thus producing a natural draft, causing some combustion to take place and the generation of sufficient heat for carbonization. This is also accomplished by the momentary use of the fan *S* after charging fuel and when *W* or *t* is open; on standing the fuel is carbonized sufficiently to make first class ashless fuel (approximately ashless when wood is the fuel used) and one that does not clinker, or cause clinker troubles.

When fuel is used which produces a smoke on starting the fire I do not leave cover *W* open when blasting the fuel but instead allow the blast gas to pass through valve *I* and out into the air, through valve *t*.

The generator pot of one or two piece construction, bottomless or nearly so, and built on the order of a crucible is a characteristic feature of my invention. This pot may be round in horizontal section, elliptical or of other shape but the most satisfactory results are obtained with the forms mentioned. The pot is made of fire resisting material and may be composed of graphite, graphite composition, special metals or alloys, fire clay materials, carborundum, or other refractory material. The advantages gained are: simplicity of construction, ease of replacing, long life, opportunity to suspend pot in a gaseous atmosphere and a means of eliminating the usual tuyère.

I recognize that the principle of making producer gas is old and I do not claim it

as my own. The apparatus herein described offers a better means of making this gas for the purpose intended and therefore,

I claim,

5. 1. In a producer gas generator, adapted for use with automotive mechanisms, a generator chamber containing solid combustible fuel comprising a cushion-suspended pot partially open at the bottom. 70
10. 2. In a producer gas generator, adapted for use with automotive mechanisms, a generator chamber containing solid combustible fuel partially open at the bottom and cushion-suspended in a gaseous atmosphere. 75
15. 3. A gas producer adapted for use with automotive mechanisms, including a generator lining cushion suspended in the air used for gas making. 80
20. 4. A gas producer adapted for use in automotive mechanisms, comprising in combination, an outer casing, an inner generator pot containing a fuel bed, and a cushion-suspension for said generator pot within said casing. 85
25. 5. A gas producer adapted for use in automotive mechanisms, comprising in combination, an outer casing, a packing ring carried by said casing, an inner generator pot containing the fuel bed and supported 90 upon said packing ring.
30. 6. A gas producer adapted for use in automotive mechanisms, comprising an outer casing, packing rings carried by said casing, an inner generator casing adapted to hold 95 the fuel bed, said inner casing having a flange adjacent its upper portion adapted to be secured between said packing rings whereby said pot is cushion-suspended within the outer casing, and means for supplying air to the space between the outer casing and the inner casing below the flange, whereby the air is superheated by contact 100 with the walls of the inner casing prior to its entry into the fuel bed. 105
35. 7. In a gas producer adapted for use in automotive mechanisms, a hollow outer jacket, a generator pot cushion-suspended within the jacket the pot being open at the top and partially open at the bottom, means 110 for supplying air to the hollow jacket, valves opening from said jacket to the spaces above and below the point of suspension of said pot, and a reversing means for simultaneously operating said valves to close the one and open the other whereby said producer is converted from a down-draft to an up-draft producer or vice-versa. 115
40. 8. A gas producer adapted for use with automotive mechanisms comprising a hollow outer shell, a generator pot cushion suspended within the jacket and open at top and bottom, a fuel feeding hopper continuously open to the generator pot and having a capacity relatively large with respect to 120 the generator, said hopper being provided with a base resting upon said hollow outer shell and sloping gently toward the center of the generator pot whereby an air space is formed above the fuel bed in said generator pot, and means for supplying air from the hollow casing to the spaces above and below the point of suspension of the generator pot. 125
45. 9. A gas producer comprising a hollow outer shell, an inner generator pot having a flange adjacent its upper portion, a pair of packing rings on the inner surface of said outer shell adapted to receive the flange of said generator pot between them, thus providing a cushion suspension for said generator pot. 130
50. 10. A gas producer adapted for use with automotive mechanisms, comprising an outer shell, a generator pot adapted to contain the fuel bed, said pot being cushion-suspended within the outer shell, a fuel feeding hopper having a capacity relatively large with respect to the generator pot, said hopper being provided with a base resting upon the said outer casing and sloping gently downwardly toward the center of the generator pot, whereby a substantial portion of the weight of the fuel is supported independently of the generator pot. 135
55. 11. A gas producer comprising a hollow outer shell, an inner generator pot having a flange adjacent its upper portion, a pair of packing rings on the inner surface of said outer shell adapted to form a cushion suspension for said generator pot; one being located above and the other supporting said flange, whereby gas-tight joints are provided between the generator pot and the outer casing, a relatively large fuel supply hopper provided with a base having a relatively gentle downward and inward slope, and resting upon the top of the outer casing and spaced above the generator pot, means for alternately admitting air to the spaces above and below the said packing rings, and means for withdrawing gas from the space opposite that at which air is admitted. 140
60. 12. A gas producer adapted for use in automotive mechanisms comprising an outer casing, packing rings carried by said casing, an inner generator casing adapted to contain the fuel bed, said inner casing having a flange adjacent its upper portion and adapted to be secured between said packing rings, whereby said pot is cushion suspended within the outer casing, and a hopper provided with a gently sloping base communicating with the fuel bed of said inner casing and supported upon the outer casing. 145
65. 13. A gas producer for use with automotive mechanisms comprising a solid fuel supply hopper and a generator pot having direct and free communication therewith whereby the passage of solid fuel is continuous from one to the other, and priming means for at times enriching the gas pro- 150

- duced in said producer comprising a liquid fuel passage leading through the fuel in the hopper to the inner zone of the generator pot.
5. 14. In an apparatus for producing gaseous fuel a combination of an up-draft and a down-draft gas producer instantly convertible from the one to the other with a means for making this change consisting in a direct connected valve arrangement for operating in synchronism the moving parts controlling the air supply and the direction of the gas.
10. 15. A gas producer adapted for use with automotive mechanisms comprising an outer shell, a generator pot adapted to contain the fuel bed and cushion suspended within the outer shell, and a fuel feeding hopper continuously open to the fuel bed of said generator pot and having a base resting upon the outer shell or casing, whereby a substantial portion of the weight of the fuel is supported independently of the generator pot.
20. 16. In a gas producer adapted for use with automotive mechanisms, a hollow outer jacket, a generator pot suspended within the jacket and open at top and bottom, a fuel hopper continuously open to the generator pot and having a base resting upon said hollow outer jacket, means for supplying air to the hollow jacket, and valves opening from said jacket to spaces above and below the point of suspension of said pot.
25. 17. In an apparatus including a producer and condenser for producing gaseous fuel suitable for use in automotive mechanisms a means of supplying cool air to the condenser under pressure and hot saturated air to the produced under pressure consisting in a funnel shaped air inlet to the condenser facing in the direction of motion of the vehicle and of sufficient size to produce the desired pressure,
30. 18. A producer gas generator for use with automotive mechanisms comprising an outer casing, and a generator pot adapted to receive combustible fuel, said pot being cushioned within the outer casing by means of shock absorbing devices.
35. 19. A generator for making producer gas for use with automotive mechanisms comprising an outer casing, a generator pot containing the fuel bed suspended within the outer casing, and shock absorbing means interposed between said pot and outer casing.
40. 20. In a producer gas generator adapted for use with automotive mechanisms, a removable grateless generator chamber containing solid combustible fuel, comprising a cushion suspended pot open at the bottom.
45. 21. In a producer gas generator, adapted for use with automotive mechanisms, a grateless generator chamber containing solid combustible matter, said chamber being open at the bottom and cushion suspended in a gaseous atmosphere.
50. 22. In an apparatus for producing gaseous fuel, a combination of an up-draft and a down-draft gas producer instantly convertible from one to the other, including a removable generator pot cushion suspended in the air used for gas making when operated as an up-draft producer, and suspended in the gas made when used as a down-draft producer, and means for changing the device from an up-draft to a down-draft producer, consisting in a direct connected valve arrangement for operating in synchronism the moving parts controlling the air supply and the direction of the gas.
55. 23. A gas producer adapted for use in automotive mechanisms, comprising in combination an outer casing, an inner removable generator pot containing the fuel bed and consisting of one piece, and a cushion suspension for said generator pot.
60. 24. A producer gas generator for use with automotive mechanisms, comprising an outer casing, a removable grateless generator pot containing the fuel bed suspended within the outer casing, and shock absorbing means interposed between said pot and outer casing.

WILLIAM W. ODELL.
